4 Sheets-Sheet 2

4 Sheets-Sheet 2

This technical drawing illustrates a mechanical assembly, likely a conveyor or transport system, featuring a series of components labeled with numbers. The assembly includes a central horizontal frame with vertical supports. A curved belt or chain mechanism is shown, supported by several components. Key labeled parts include:

- 66, 65, 73: Located at the top left, these components appear to be bushings or bearings.
- 62: A curved component, possibly a deflection plate or a part of the conveyor belt.
- 30: A horizontal component, possibly a conveyor belt support or a frame part.
- 25, 26: Components located on the left side of the main assembly.
- 15: A curved component, likely a conveyor belt or a deflection plate.
- 51: A circular component, possibly a pulley or a wheel.
- 59, 62, 60: Components located on the right side of the main assembly.
- 57: A component located near the bottom right.
- 53, 55: Components located on the far right side.
- 80, 85, 86, 87, 88, 89, 90, 91, 92, 93: Components located at the bottom, possibly related to the base or a specific mechanism.

UNITED STATES PATENT OFFICE

WILLIAM A. MATHESON, OF CHICAGO, ILLINOIS, ASSIGNOR TO ROLL-A-WAY BED CORPORATION, OF CHICAGO, ILLINOIS, A CORPORATION OF ILLINOIS

MASSAGING AND EXERCISING APPARATUS

Application filed August 8, 1927. Serial No. 211,441.

My invention relates to massaging and exercising apparatus and has among its other objects, the production of apparatus of the kind described that is exceedingly compact in construction and is provided with means whereby a relatively large variety of exercises may be practiced.

A particular object of the invention is to provide an improved truck for supporting the apparatus when it is not in use.

Another particular object of the invention is to provide apparatus of the kind described having improved mechanism whereby rowing exercises may be practiced.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a plan elevation of a device which embodies the invention;

Fig. 2 is a side elevation of the improved device;

Fig. 3 is an end elevation of the improved device shown in Figs. 1 and 2, a collapsible truck which forms part of the device being illustrated as it appears when it is not collapsed;

Fig. 4 is a section taken on line 4—4 of Fig. 1;

Fig. 5 is a section taken on line 5—5 of Fig. 1;

Fig. 6 is a section taken on line 6—6 of Fig. 1;

Fig. 7 is a section taken on line 7—7 of Fig. 1;

Fig. 8 is a section taken on line 8—8 of Fig. 4;

Fig. 9 is a section taken on line 9—9 of Fig. 8;

Fig. 10 is a fragmentary plan elevation of a device embodying another form of the invention; and

Fig. 11 is a section taken on line 11—11 of Fig. 10.

Referring for the present to Figs. 1 to 9, inclusive, wherein I have illustrated one form of my invention embodied in a device which resembles, to some extent, the devices shown in my copending application, Serial No. 180,278, filed April 1st, 1927, the reference characters 15 and 16 designate longitudinally extending side members of a frame which supports my improved massaging and exercising apparatus. The side members 15 and 16 may be of any suitable construction but I preferably form them from sheet metal, each of the side members preferably comprising beams 18 and 19 which extend between posts or columns 20 and 21. The space between the beams 18 and 19 of each of the side members is preferably closed by webs 22 which, of course, cause the side members to become relatively rigid. It will be noted that an arcuate portion 24 of each of the beams 18 is provided with means for mounting a plurality of rollers 25 and that these rollers are arranged so that they conform approximately to the curvature of one's back. As set forth in the above-mentioned copending application, this insures that they will thoroughly massage the muscles of the back when the apparatus is used for this purpose. It will be noted that the portions of the beams 18 and 19 intermediate the rollers 25 and the posts or columns 21 are also arcuate and are so designed that they are at a lower elevation than the arcuate portions 24. This construction allows one to

quickly and easily seat oneself upon the rollers 25 and then place one's feet in the stirrups hereinafter described.

The rollers 25 are preferably formed from some resilient material such as rubber and each of the rollers is preferably mounted upon a rod or shaft 26 which has its ends rotatably journaled in bores 27 formed in bearing members 28 which are mounted in the beams 18. Each bearing member 28 is rigidly secured to its associated beam 18 by a bolt 29 and the bolts are arranged so that they limit longitudinal displacement of the rods or shafts 26 (see Fig. 6).

I prefer to make the aforementioned posts

or columns 21 somewhat taller than the posts 20 so that hand grips 31 projecting inwardly from the posts may be preferably positioned with respect to the rollers 25. The purpose 5 of the hand grips 31 is set forth in detail in my aforementioned copending application. The posts 21 also carry pins 33 to which sandals or stirrups 34 are secured, the construction being such that when one lies on the 10 rollers 25, one's feet may be inserted in the stirrups and the body may be drawn back and forth over the rollers to massage it.

Adjustably secured to the side frames 15 and 16 are hand grips 36 which, as best shown 15 in Fig. 7, are secured to rods 38 which are pivoted by pins 37 to rods 39, the rods 38 and 39 being slidably journaled in bores 40 formed in the tubular members 41. The tubular members 41 are rigidly secured in the side 20 frames 15 and 16 and, in addition to the bores 40, are provided with bores 43 to communicate with the bores 40 through bores 44 of relatively small diameters. Slidably journaled in bores 44 are bolts 45 which have their 25 upper ends screw-threaded into the lower ends of the rods 39. Carried by the means of the bolts 45 are washers 47, or the equivalent, which preferably fit snugly in the bores 43 and limit displacement of the bolts 45 in an 30 upward direction. However, the construction is such that the rod 39 associated with each hand grip 36 may be brought into a position corresponding to the position in which one of the rods 39 is shown in Fig. 7. This 35 permits the hand grip 36 and its associated rod 38 to be brought into the positions wherein they are shown in dotted lines in Fig. 7 so that the improved massaging and exercising device may be stored under a bed, or the like, 40 when not in use. This construction is similar to the construction shown in my copending application.

Extending between the side frames 15 and 16 intermediate the ends thereof is a transverse frame member 50 which carries a housing 51. Journaled in the housing 51 is a substantially U-shaped bar 52 to which a pulley 53, or the equivalent, is rigidly secured, the pulley being disposed within the housing 51. A belt 55, or the equivalent, which has one of its ends secured by rivets 57 to the frame member 50 is trained around the pulley 53 and has its other end secured to one end of a bolt 59, or the equivalent, which is slidably journaled in the frame member 50. Interposed between the frame member 50 and a wing nut 60 screw-threaded upon the bolt 59 is a helical compression spring 62 which draws the belt 55 into frictional engagement 55 with the periphery of the pulley 53. Obviously, the wing nut 60 may be manipulated to regulate the tension to which the belt 55 is subjected.

60 The two substantially parallel arms of the U-shaped bar 52 are identified by the refer-

ence character 64 and, as best shown in Fig. 8, the arms 64 are preferably tubular so that tubes 65 may telescope therein. Rigidly secured to the outer end of each tube 65 is a hand grip 66 which may be brought into a plurality of adjusted positions by sliding the tube into or out of the associated arm 64. Means is preferably provided for locking the tubes 65 in adjusted positions in their respective arms 64, this means preferably comprising, in each instance, a pin 67 having a head 68 engageable with apertures 69 formed in the associated tube. Each pin 67 is slidably mounted in a tubular member 70 which is rigidly secured to the associated arm 64, a compression spring 71 being interposed between the head 68 and the tubular member 70 to urge the head toward the associated tube 65. A head 73 is preferably provided upon the outer end of each pin 67 so that the pin may be withdrawn from the apertures 69. It is readily understood that with this arrangement, the hand grips 66 may be locked in a plurality of adjusted positions with respect to the pivotal axis of the U-shaped bar 90 52.

At one of its ends, the frame is preferably provided with a transverse bar 76 which is rigidly secured to the side members 15 and 16. Secured to the transverse bar 76 is a collapsible truck which is designated in general by the reference character 78. The truck 78 preferably comprises two U-shaped bars 80 and 81 and the U-shaped bar 81 has a flat bar 83 secured to it, the flat bar 83 being secured by screws 84, or the equivalent, to the transverse bar 76. The U-shaped bar 80 is secured by hinges 86 to the bar 81 and it may be brought into the position wherein it is shown in full lines in Fig. 4 when the improved exercising and massaging device is in use. However, when the truck is to be used to support the improved device, the bar 80 is brought into the position wherein it is shown in dotted lines in Fig. 4 so that the device may be turned up on end. The U-shaped bars 80 and 81 are each preferably provided with a plurality of casters 88 so that the improved device may be wheeled into any desired position. Thus, the device 100 may be stored in a closet, or the like, when 105 not in use.

It will be noted that each of the U-shaped bars 80 and 81 is provided with a groove 90 adapted to hold a strip of felt 92, or of any 110 equivalent, compressible material such as rubber, so that when the device is wheeled across a room, or the like, the truck will not mar the walls or furniture of the room. It will also be noted that when the improved 115 device is placed on end and is supported by the truck, all parts thereof are within the boundaries of the truck. In the illustrated embodiment of the invention, the columns or 120 posts 20 and 21 are provided with tips or feet 125 130

93 which are preferably formed of rubber, felt, or some other material which will not mar the surface upon which the improved device is supported when the device is in use.

The manner in which the rollers 25 are employed to massage the body is explained in detail in my aforementioned copending application and in the same application, I have explained the purpose of the hand grips 31 and 36 and the stirrups 34. With respect to the hand grips 66, it will be readily understood that one may sit upon the rollers 25 and place one's feet in the stirrups 34 and then practice a rowing exercise by moving the hand grips 66 against the action of the belt 55 upon the pulley 53. Obviously, the person taking the exercise may adjust the spring 69 as desired and may bring the hand grips 66 into convenient positions with respect to the pivotal axis of the U-shaped bar 52.

Referring now to Figs. 10 and 11, wherein I have shown apparatus embodying another form of the invention, the reference character 100 designates a frame which is substantially identical with the frame shown in Figs. 1 to 9, inclusive, the frame 100 being provided with rollers 101 and hand grips 102 and 103 which correspond to the aforementioned rollers 25 and hand grips 31 and 36, respectively. The frame is also provided with stirrups 104 which correspond to the aforementioned stirrups 34. In Figs. 10 and 11, I have not shown the entire device but it is readily understood that the frame 100 is preferably mounted upon a truck which corresponds to the truck 78.

In place of the U-shaped bar 52 and the apparatus associated therewith, I have provided two substantially L-shaped bars 106 comprising tubular arms 107 in which tubes 108 telescope. Hand grips 110 are secured to the outer ends of the tubes 108 and pins 111 substantially identical with the aforementioned pins 67 are provided for securing the tubes 108 and the hand grips 110 in adjusted positions with respect to the tubular arms 107. Each bar 106 comprises a shaft portion 114 which is pivotally mounted in a housing 115 carried by a transverse bar 116 which constitutes part of the frame 100. Constrained to rotate with each shaft portion 114 is a pulley 117 around which a belt 118 is trained. One end of the belt 118 is secured by rivets 120, or the equivalent, to the transverse bar 116 and the other end of the belt is secured to one end of a bolt 122, the bolt 122 being slidably journaled in the transverse bar 116. A compression spring 127 is disposed around each bolt 122 and is interposed between the bar 116 and the wing nut 128 screw-threaded upon the bolt. Obviously, the wing nut 128 may be manipulated to regulate the tension which the associated spring 127 exerts upon the associated belt 118.

The apparatus shown in Figs. 10 and 11 is employed in substantially the same manner as the apparatus shown in Figs. 1 to 9, inclusive, with the exception, however, that the hand grips 110 of Figs. 10 and 11 may be displaced independently of each other while the hand grips 66 shown in Fig. 4 must be angularly displaced in unison around the pivotal axis of the U-shaped bar 52.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. Apparatus of the kind described comprising a frame, a plurality of rollers arranged transversely in one portion of said frame and spaced from one end thereof, said rollers disposed in a convex curve longitudinally of said frame, the portion of the frame intermediate said rollers and said end being lower in height than the portion in which the rollers are mounted, foot rests at said end, a pulley rotatably mounted in said frame, a belt frictionally engaging the pulley to resist rotation thereof, and a lever manually operable to angularly displace said pulley against the action of said belt.

2. Apparatus of the kind described comprising a frame, a plurality of rollers revolvably mounted on said frame and spaced from one end thereof, means adjacent said end for engaging the feet of a person supported on said rollers, a pair of levers mounted on said frame between said rollers and said end and movable toward said rollers and toward said end, and means for rendering difficult the movement of said levers.

3. Apparatus of the kind described comprising a frame, a plurality of rollers revolvably mounted in a convex arc on said frame and spaced from one end thereof, means adjacent said end for engaging the feet of a person supported on said rollers, a pair of levers mounted on said frame between said rollers and said end and movable toward said rollers and toward said end, and means for rendering difficult the movement of said levers.

4. Apparatus of the kind described comprising a frame, a plurality of rollers revolvably mounted on said frame and spaced from one end thereof, means adjacent said end for engaging the feet of a person supported on said rollers, a pair of levers mounted on said frame between said rollers and said end and movable toward said rollers and toward said end, a pulley secured to said levers for movement therewith, and means for yieldably restraining rotation of said pulley.

5. Apparatus of the kind described comprising a frame, a plurality of rollers revolvably mounted in a convex arc on said frame and spaced from one end thereof, means adjacent said end for engaging the feet of a person supported on said rollers, a pair of levers mounted on said frame between said rollers and said end and movable toward said rollers and toward said end, a pulley secured to said levers for movement therewith, and means for yieldably restraining rotation of said pulley.

6. Apparatus of the kind described comprising a frame, a plurality of rollers revolvably mounted on said frame and spaced from one end thereof, means adjacent said end for engaging the feet of a person supported on said rollers, a pair of levers mounted on said frame between said rollers and said end and movable toward said rollers and toward said end, a pulley secured to said levers for movement therewith, and means for frictionally restraining rotation of said pulley.

7. Apparatus of the kind described comprising a frame, a plurality of rollers revolvably mounted in a convex arc on said frame and spaced from one end thereof, means adjacent said end for engaging the feet of a person supported on said rollers, a pair of levers mounted on said frame between said rollers and said end and movable toward said rollers and toward said end, a pulley secured to said levers for movement therewith, and means for frictionally restraining rotation of said pulley.

In witness whereof, I have hereunto signed my name.

WILLIAM A. MATHESON.
